UNITED STATES PATENT OFFICE.

JOHN T. MORGAN, OF SELMA, ALABAMA, AND HENRY F. HAYDEN, OF WASHINGTON, DISTRICT OF COLUMBIA.

GAS-FURNACE FOR METALLURGIC AND OTHER PURPOSES, AND METHOD OF OPERATING THE SAME.

SPECIFICATION forming part of Letters Patent No. 291,586, dated January 1, 1884.

Application filed April 13, 1883. (No model.)

To all whom it may concern:

Be it known that we, JOHN T. MORGAN, a resident of Selma, in the county of Dallas and State of Alabama, and HENRY F. HAYDEN, a resident of Washington city, in the District of Columbia, citizens of the United States, have invented certain new and useful Improvements in Gas-Furnaces for Metallurgic and other Purposes, and Methods for Operating the Same; and we hereby declare the following to be a full, clear, and exact description of the same, reference being had to the accompanying drawings, forming part of the same, in which—

15 Figure 1 is a longitudinal vertical section of a furnace having our invention applied thereto. Fig. 2 is a horizontal section of the same on the dotted line, Fig. 1. Fig. 3 is an enlarged detached view of the burner. Fig. 4 is a transverse section of the burner on the dotted line, Fig. 3. Fig. 5 is an enlarged detached view of one of the "tuyere-walls" of the mixing-chamber.

Like letters refer to like parts wherever they 25 occur.

Our invention relates, broadly, to the construction of the fire-chambers of that class of furnaces wherein gaseous fuel is used, either in the form of vaporized hydrocarbons or as 30 fixed gas, for manufacturing purposes generally, and has for its object to obtain such perfect control of the combustion that the nature or character of the flame can be changed at will from neutral to oxidizing, or the reverse; 35 or, if the quality of the flame is immaterial, then complete combustion can be insured and a clear, smokeless flame always secured.

In metallurgic operations it is of material 40 importance to be able to control the character of the flame, as for some purposes and under certain conditions a neutral flame is desirable, while at other times an oxidizing-flame is required, and as our invention is especially adapted to such processes, we have shown it 45 in connection with a metallurgic furnace, but do not wish or intend to be limited to such an application. As in melting, warming in, and flattening glass and many other manufacturing processes a clear, smokeless flame is a 50 great desideratum, it will be evident that our

invention is eminently suitable for such furnaces.

To this end, therefore, our invention embraces three main features, viz: First, the burner having the form of a longitudinally-slotted hollow cylinder with perforated jacket, or of general C-form in cross-section, whereby the gaseous fuel or vapors may be disseminated over the whole surface of the burner and fully presented to the air-supply, so as to obtain complete or perfect combustion, while, if desired, an additional supply of air, steam, or combustible gas or vapor may be admitted to the center of the hollow cylinder, and, being emitted therefrom through the longitudinal slot of the cylinder, will vary the character of the flame according to the nature of the gas, &c., employed; second, in the combination of such a burner with an air-mixing chamber having interrupted or tortuous passages, 55 which cause the thorough intermingling of the air, gases, &c., so as to render the flame of uniform character, the quality of the flame depending on the relative proportions of air, steam, and gas or hydrocarbon vapors admitted and admixed; third, in constructing the walls which form the tortuous passages of the mixing-chamber of a series of hollow perforated fire-brick partitions, which we term "tuyere-walls," so that there may be introduced into the flame in the mixing-chamber, at any time before it reaches the working-chamber, either steam, air, or gas, or all three, so as to change at will the nature of the flame. There are also minor features, which will hereinafter more fully appear.

We will now proceed to describe our invention more specifically, so that others skilled in the art to which it appertains may apply the same.

In the drawings, A indicates the walls of a furnace of any suitable character for the work to be performed. In the present instance it is a puddling-furnace with hearth *a* and stack *a'*.

At that part of the furnace usually occupied by the fire-chamber, its grate, &c., we form an air chamber or well, B, into which, preferably near the bottom, we admit the air to supply combustion by means of an air-pipe, C, which should have a valve, *c*, and may connect with

a fan or other suitable means of obtaining a forced blast, if desired.

In order to obtain access to the air chamber or well B, a door or man-hole, b, is provided. 5 The air-well B connects above the mixing-chamber D, which delivers into the working-chamber of the furnace.

Arranged in the upper part of the air chamber or well B, and opposite the mouth of the 10 mixing-chamber, is the burner E. This burner E is in the form of a hollow jacketed cylinder, slotted longitudinally, as at c^2 , Fig. 4, so as in cross-section to have the general form of the letter C. The jacketing of the cylinder forms 15 an uninterrupted annular chamber, c, (see Fig. 4,) which is supplied with combustible gas or vapor by a valved supply-pipe, c', which may enter the air-well B directly through the rear wall, as shown in Fig. 1, or through the side wall, as shown in Fig. 2, whichever may be found more practicable or convenient. The outer shell or jacket is perforated at intervals all around, so that any number of fine jets of 20 gas are projected from the cylindrical burner 25 in all directions, and being met by the air-blast from the well B, which envelops the cylinder, very perfect combustion can be obtained.

F indicates a valved pipe, which delivers 30 into the tubular center of the burner E. The opposite end of the burner is closed by the wall 35 of the furnace or by a suitable head. This pipe F is employed either to deliver air, steam, liquefied bitumen, vaporized hydrocarbons, or fixed gases, according to the object in view; but whatever is so delivered to the center of 40 burner E will issue in a sheet through slot c, and in order to obtain a uniform discharge along the whole length of the burner, it is preferable to cause the slot to diverge or widen gradually from the receiving end (pipe F) to the opposite end.

D indicates the mixing-chamber, which, in its simplest form, will consist of a series of pendent and standing cross-walls extending 45 up or down somewhat less than the height of chamber D, so as to form interrupted or zig-zag passages, which thoroughly break up and intermingle the flame, gases, &c. The preferred form of these walls d, however, is that 50 shown in the drawings—that is to say, they may be made of German fire-clay or other suitable highly refractory material, with sloping sides, hollow center, and perforated walls. The hollow center and perforated walls enable 55 us to introduce into the flame either steam, air, hydrocarbon vapors, gases, or several of these agents at once, and thus to temper, control, and change the character of the flame in the mixing-chamber just as it enters the working-chamber.

For the purpose of supplying gas, air, &c., to the hollow perforated tuyere walls d, a series of supply-pipes, d' d'' d'', with suitable valves, are provided. By making the parts d tapering, we 65 are enabled to withdraw the old tuyeres d when injured and replace them with new, the pend-

ants being simply lifted out, while those in the bridge-wall may be withdrawn through the side of the furnace, as at e; or, if preferred, those in the bridge-wall may be built in. 70 Where the tuyere-walls d are inserted, as first specified; the joints between the parts d and the furnace-walls will be luted up in the usual way.

Owing to the preferred form and the function of the parts d, we have termed them 75 "tuyere-walls."

The construction being substantially as hereinbefore specified, the device will operate as follows: Vapors of hydrocarbon or combustible gas, having been admitted (from any suitable generator or source) through supply-pipe c' to annular chamber c of burner C, issue in fine jets all over the surface of the cylinder, where the jets meet and combine with the blast 80 rising in air-well B, which air-blast will, as it is under pressure and confined by the side walls, completely envelop the cylindrical burner and insure complete combustion thereat. The highly-heated products of combustion will 85 then be projected into the tortuous passages of mixing-chamber D, whence they pass to the working-chamber of the furnace. Where a clear flame is desired, the furnace may have only this construction, or, if constructed as 90 fully shown, may only be so operated. Where, however, an oxidizing-flame is required, steam may be admitted (or an additional supply of air) by means of pipe F to the center of the cylindrical burner, and will be projected in a 95 sheet through the slot c'; or, if a neutral or smoky flame is desired, bituminous matters, hydrocarbons, or hydrocarbon vapors may be passed through pipe F into the center of the burner E, and, issuing therefrom, will surcharge 100 the flame with carbonaceous matter, and thus change its character. It will thus be seen that by means of the burner shown and the mixing-chamber the character and quality of the 105 flame can be sufficiently well controlled for most manufacturing purposes. When it is desired, however, to further manipulate the flame before it enters the hearth, air, steam, or gases (either or all) may be introduced into the 110 flame in the mixing-chambers, as before 115 specified.

In treating various ores, metal, &c., it is sometimes desirable to introduce hydrocarbon vapors and other gases into or over the mass in the working-chamber, and for this purpose we have provided pipes H, which may open 120 into the hearth a by one or more branches, h, at any desirable point, so that an atmosphere of hydrocarbon-gas may be maintained in the working-chamber above the metal. These 125 pipes H preferably enter at the rear of the furnace, on opposite sides and just below the bridge-wall, as shown, so that after the treatment of the metal upon the hearth a, when the fire has been drawn and before removing the 130 metal from the hearth, it may be subjected to the action of carbonaceous vapors or gases

by admitting said gases through the pipes H and permitting them to fill the working-chamber.

The advantages of our invention are that by 5 means very simply and readily repaired we are enabled to perfectly control the flame of gas-furnaces, so as to obtain either a neutral or an oxidizing flame or the most perfect combustion with intense heat and a clear flame, 10 thus adapting the gas-furnaces to the wants of manufacturers.

Wherever herein we have used the word 15 "flame" with reference to the burner and initial combustion, we wish to be understood as indicating the highly-heated gaseous products resulting from complete combustion.

We are aware that it is a common custom to use hollow perforated bridge-walls, perforated pipe, and like device for injecting air and steam 20 into the products of combustion after they have left the grate or fire-chamber and before they enter the working-chamber, in order to insure oxidation of the gases and complete combustion; and we are also aware that it has been 25 proposed to vary the chemical character of the flame by supplying the air and gas in measured quantities at the initial point of combustion, and do not herein claim the same; but we are not aware that it has ever been proposed 30 to introduce air and gases into the highly-heated products of perfect combustion in a mixing-chamber before the same enter the working-chamber, in order to control the character of the flame, so as to render it oxidizing, neutral, 35 or smoky, and thus avoid the reduction of the temperature at the initial point of combustion, which results from the former methods; and therefore,

Having thus described our invention, what 40 we claim, and desire to secure by Letters Patent, is—

1. The method herein described for controlling and varying the character of the flame in metallurgic and like furnaces, which consists in 45 first bringing together the proper volumes of air and gas to produce complete combustion at

the point of initial combustion, and then sur- 50 rounding the flame with oxidizing or carburizing gases between the point of initial combustion and the working-chamber of the furnace, substantially as and for the purposes specified.

2. A burner for gas-furnaces, having a general C form in cross-section, and consisting of a longitudinally-slotted hollow cylinder having a reticulated or closely-perforated jacket, sub- 55 stantially as and for the purpose specified.

3. In a gas-furnace, the combination of a burner consisting of a hollow longitudinally-slotted cylinder having a perforated jacket, and a supply-pipe arranged to deliver into the hollow center of the longitudinally-slotted burner, 60 substantially as and for the purpose specified.

4. In a gas-furnace, the combination of a burner consisting of a hollow longitudinally-slotted cylinder having a perforated or reticulated jacket, and a mixing-chamber having a series of pendent and projecting walls which divide the chamber into zigzag or irregular 65 passages, substantially as and for the purpose specified.

5. In a gas-furnace, the combination, with a mixing-chamber divided into zigzag passages by a series of hollow perforated projecting walls, of a gas-burner arranged at the mouth of the mixing-chamber to deliver the flame there- 70 to, substantially as and for the purpose specified.

6. In a mixing-chamber for metallurgic and similar gas-furnaces, the combination of a series of hollow, perforated, detachable cross-walls of less height than the mixing-chamber, and arranged alternately above and below to form zigzag or irregular flame-passages, 75 substantially as and for the purpose specified.

In testimony whereof we affix our signatures, 80 in presence of two witnesses, this 12th day of April, 1883.

JOHN T. MORGAN.
